(57) **CLAIM**

The ornamental design for a kryogun with LED light attachment, as shown and described.

DESCRIPTION

FIG. 1 is a side perspective view of a kryogun with LED light attachment showing my new design;

FIG. 2 is a front view of a kryogun with LED light attachment;

FIG. 3 is a back view of a kryogun with LED light attachment;

FIG. 4 is a right side view of a kryogun with LED light attachment;

FIG. 5 is a left side view of a kryogun with LED light attachment;

FIG. 6 is a top view of a kryogun with LED light attachment;

FIG. 7 is a bottom view of a kryogun with LED light attachment; and,

FIG. 8 is a side view of a kryogun with LED light attachment in use.

The broken lines shown in the drawings are for illustrative purposes only and form no part of the claimed design.
